METHOD AND APPARATUS FOR TREATING
NAILS

Conrad C. Calvin, New York, N. Y.

Application May 6, 1935, Serial No. 19,976

31 Claims. (Cl. 132—73)

This invention relates to a new and useful improvement in a method and apparatus for treating nails such as finger and toe nails.

In the treatment and beautifying of such nails, there are generally three sections or portions of the nail which may be and generally are treated as distinct portions for separate treatment, namely the moon section, the middle section, and the tip section. This same distinction and treatment applies to both finger and toe nails.

Sometimes it is desired to have just the middle or main portion covered with nail polish or coloring matter, leaving the tip and moon in their natural color. At other times, the moon alone is left natural in color with the rest of the nail covered with nail polish or coloring matter. In other cases the tip and the moon are to be treated as well with coloring material, sometimes white in color, to more clearly define these sections, 20 with the middle section colored with a contrasting color. These variations in the treatment of the nail and many others which may be conceived as the person may desire, are generally achieved by artistic hand work which requires great skill 25 and takes considerable time even for an expert and a large amount of time and patience when the amateur person is trying to achieve this result by himself, but even then it cannot be done without the colors running or blending into each 30 other and without clear lines of demarcation between the contrasting colors.

It is therefore a main object of this invention to provide a method and apparatus whereby the above and similar results may be achieved by 35 any one, whether expert or not, with ease and with a great saving in time and effort.

A further object is to provide a simple and efficient device in the form of a stencil, mask or ornamental design mask which is used on the 40 nail to facilitate the application of the method to the treatment of the nail, whereby the ornamental beautifying effects can be produced with ease and speed and with very clear defined lines of demarcation between the various colors.

45 Further and more specific objects, features, and advantages will more clearly appear from a consideration of the specification hereinafter when taken in connection with the accompanying drawing which forms part of the specification and which illustrates a present preferred form which the invention, among others may assume.

In a general contemplation of the invention, it includes a stencil of predetermined form which 50 can be applied to the nail to cover a predeter-

mined portion of the nail while the remainder of the nail is being treated. For example, the stencil, mask, or design mask, may be disposed over the moon portion of the nail while the middle portion of the nail is being treated, with the 5 adjacent edge of the stencil shaped with the configuration of the desired moon so that after the middle portion of the nail is finished, the stencil is lifted off and there results a well defined outer edge to the moon which is clear and 10 precise and of any desired shape and size. The same general procedure can be employed with respect to the tip of the nail as desired and as will be clearly and in detail set forth and described hereinafter. 15

The novel method in the course of which the stencil is employed, is, in one form, generally as follows:

1. The nail is thoroughly cleaned;
2. The moon portion is then covered roughly 20 with a white polish and allowed to dry thoroughly;
3. A stencil of the desired size and shape is then placed over this moon portion with its outer edge of the desired shape disposed in the desired 25 position on the nail. This stencil is made of any suitable material which is generally relatively thin and pliable such as paper, Cellophane, celullosic or fibrous material, and the like but in the most preferred embodiment is preferably one 30 which is not affected by any of the substances applied to the nail, the finger, or the cuticle such as nail polishes, nail polish removers, cleansers and the like, so that it is impervious to them and they will not get through the material while it is 35 on the nail. The material is preferably provided on its under surface in contact with the nail proper or the nail polish with a suitable adhesive which may be any desired adhesive applied over the entire surface of that portion of the mask 40 which it is intended to press into intimate contact with the nail proper or the nail polish already on the nail but which adhesive in the most preferred embodiment is one which is neither soluble in nor affected nor destroyed by the usual 45 nail polishes, removers, cleansers, etc., such as alcohol, acetone and other nail treating substances and which is preferably of a non-drying nature so that the stencil, mask, or design mask, can be properly adhered to the nail or polish and yet can be quickly and easily removed without affecting the surface of the nail or polish or leaving parts of the stencil or adhesive sticking to the nail or polish upon removal of the stencil. Adhesives which have been tried out and found 50 55

polish is wiped off with a polish remover from this moon section leaving a natural moon section or other shape 17 shown in Fig. 2c. Thereafter this moon section is covered as in Fig 2d with 5 polish 18 of a color contrasting with the color 13. This is allowed to dry or set and then the stencil 15 is removed leaving a very clear and definite line of demarcation between the main portion of the nail and the moon section. If it 10 is desired to produce a contrasting or distinct tip portion, then the tip stencil 19 is placed as shown in Fig. 2f a little to the rear of the ordinary tip of the nail with its convex edge in line with the inner curve of the desired tip portion. 15 Then the color 13 ahead of the stencil 19 is wiped off the tip section 20 as shown in Fig. 2g and thereafter is covered with a contrasting color 21 as shown in Fig. 2h or, if desired, this tip portion may be left in its natural color. After this color 20 has dried or set, the stencil or mask 19 is removed leaving a well defined line of demarcation between the main nail portion and the tip portion, as shown in Fig. 2i, in which it is shown to be possible to cover the nail with three contrasting 25 colors.

In Figs. 3a, b, c, d, and e is illustrated another form of the invention in which it is proposed to place an ornamental design mask on the main portion of the nail and leave a natural color 30 moon. In carrying out this process or method, a thoroughly cleaned nail is covered as shown in Fig. 3a with the stencil 11 of any desired size and shape, preferably as shown, and the exposed portion of the nail is then covered with a colored 35 nail polish such as 13. In the next step, after the polish 13 has thoroughly dried, an ornamental design mask 27, such as one formed in the shape of the letter G, and made of the above mentioned material and supplied with the above 40 mentioned adhesive, is placed as shown in Fig. 3b on top of the colored polish 13. Then the colored polish exposed in Fig. 3b is wiped off, leaving the nail as shown in Fig. 3c. After this, a contrasting colored polish is, if desired, placed 45 around the nail on the exposed portions, resulting in the appearance shown in Fig. 3d. After this contrasting colored polish has set or dried for a short while, the stencil 11 and the design 50 mask 27 are removed leaving the design form in one color with the main body of the nail remaining in a contrasting color and with the moon 28 in its natural color.

With regard to the method shown in Fig. 3, it 55 is to be observed that after the first step shown in Fig. 3a is completed, the stencil 11 can be removed thus leaving the natural moon with the rest of the nail in the color 13 without any design or other contrasting color thereon. This 60 part of the method is very simple and efficient and may often be preferred as is without any of the further described steps.

In Figs. 4a, b, and c another modification of the method is shown in a permanent stencil as applied to the moon section of the nail. In this 65 case a stencil 22 is applied in the same manner as in Fig. 1b to the moon section. The exposed nail in Fig. 4b is then covered with a foundation color 13 and then the excess tail portion 23 of the stencil 22 is then cut off along the edge of the cuticle 24 and the remainder pasted down to 70 form a complete moon 25 as shown in Fig. 4c.

Fig. 5 illustrates a variety of forms of stencils, masks, and design masks which may be employed in connection with this treatment and the various 75 modifications of the general method shown and

described heretofore. In Figs. 5a, b, and c are the forms employed and shown in the above described methods, in which a and b may be reversed so as to slenderize the nail and the sides of these stencils may be used as straight edges, 5 and c may be used as a moon stencil instead of stencil 11 in Fig. 1b or instead of stencil 15 in Fig. 2b. Fig. 5e shows a form of mask or stencil which has a plurality of differently shaped edges and embodies the stencil configurations shown 10 in Figs. 1, 2, 3, and 4 and in addition has a point 26 which could be used as a tip stencil in place of the stencil 19 when the tip of the nail is cut in a pointed manner, or as a moon stencil in place of the stencil 11 in Fig. 1b. 15

Figs. 5d, f, g, h, and i illustrate a series of different forms of design masks which may be employed on the nail when it is desired to impose thereon a definite design to enhance the beauty of the nail and this ornamental design mask may 20 in the manners described above be colored or tinted in a contrasting manner if desired. It is understood that these design masks may be put on before the color is applied or after the color is applied and may be removed or left permanently on the nail, to suit the taste of the user. 25

All these stencils, masks, and design masks above described are preferably made of a suitable material which is flexible and impervious to the usual polishes, removers, cleansers and the 30 like employed in nail treatment so that when in place to cover or protect a predetermined portion of the nail, the polish, removers, cleansers, etc., can not get through or around the stencil, mask, or design mask to affect the covered or protected 35 area. These stencils, masks or design masks, may be made of any suitable material such as a cellulosic substance, waxed papers, masking tape, and the like, and may be transparent, translucent, or opaque and of any color, and may be 40 designed to be removable or permanent on the nail. They may be cut ready for use or cut by the user at will.

Preferably and necessarily the surface of the stencil, mask, or design mask employed adjacent and in contact with the nail or the nail coating must be supplied with an adhesive which may be applied thereto when the device is made or just before the device is to be applied to the nail. This adhesive is preferably one which is non-drying, at least when the temporary form of the 50 stencil, mask, or design mask is being used, so that it can be removed with ease from the nail and will not leave any adhesive or portion of the device on the nail or on the underlying polish 55 as it is being removed. This adhesive furthermore must be such as to resist the action of the usual polishes, removers, lacquers, etc., employed so that its adhesive action is not affected by coming into contact with such substances. Such 60 adhesives may be such as various gums, gum tragacanth, gum acacia, Irish moss, starches, sugars, latex bases, etc., either drying or non-drying as the use may demand as above indicated. Thus in effect the adhesive on the mask 65 forms an impenetrable barrier to the invasion into the protected area of any of the nail treating substances mentioned and therefore it is possible that the adhesive itself without the mask may in desired instances, be employed and 70 achieve these results.

When a permanent mask, stencil or design mask is employed in final position to be permanently applied to the nail, a colorless or other substance such as a liquid of a fixing nature may 75

polish is wiped off with a polish remover from this moon section leaving a natural moon section or other shape 11 shown in Fig. 2c. Thereafter this moon section is covered as in Fig 2d with 5 polish 18 of a color contrasting with the color 13. This is allowed to dry or set and then the stencil 18 is removed leaving a very clear and definite line of demarcation between the main portion of the nail and the moon section. If it 10 is desired to produce a contrasting or distinct tip portion, then the tip stencil 19 is placed as shown in Fig. 2f a little to the rear of the ordinary tip of the nail with its convex edge in line with the inner curve of the desired tip portion. 15 Then the color 13 ahead of the stencil 19 is wiped off the tip section 20 as shown in Fig. 2g and thereafter is covered with a contrasting color 21 as shown in Fig. 2h or, if desired, this tip portion may be left in its natural color. After this color 20 has dried or set, the stencil or mask 19 is removed leaving a well defined line of demarcation 25 between the main nail portion and the tip portion, as shown in Fig. 2i, in which it is shown to be possible to cover the nail with three contrasting colors.

In Figs. 3a, b, c, d, and e is illustrated another form of the invention in which it is proposed to place an ornamental design mask on the main portion of the nail and leave a natural color 30 moon. In carrying out this process or method, a thoroughly cleaned nail is covered as shown in Fig. 3a with the stencil 11 of any desired size and shape, preferably as shown, and the exposed portion of the nail is then covered with a colored 35 nail polish such as 13. In the next step, after the polish 13 has thoroughly dried, an ornamental design mask 27, such as one formed in the shape of the letter G, and made of the above mentioned material and supplied with the above 40 mentioned adhesive, is placed as shown in Fig. 3b on top of the colored polish 13. Then the colored polish exposed in Fig. 3b is wiped off, leaving the nail as shown in Fig. 3c. After this, a contrasting colored polish is, if desired, placed 45 around the nail on the exposed portions, resulting in the appearance shown in Fig. 3d. After this contrasting colored polish has set or dried for a short while, the stencil 11 and the design mask 27 are removed leaving the design form in 50 one color with the main body of the nail remaining in a contrasting color and with the moon 28 in its natural color.

With regard to the method shown in Fig. 3, it is to be observed that after the first step shown 55 in Fig. 3a is completed, the stencil 11 can be removed thus leaving the natural moon with the rest of the nail in the color 13 without any design or other contrasting color thereon. This part of the method is very simple and efficient 60 and may often be preferred as is without any of the further described steps.

In Figs. 4a, b, and c another modification of the method is shown in a permanent stencil as applied to the moon section of the nail. In this 65 case a stencil 22 is applied in the same manner as in Fig. 1b to the moon section. The exposed nail in Fig. 4b is then covered with a foundation color 13 and then the excess tail portion 23 of the stencil 22 is then cut off along the edge of 70 the cuticle 24 and the remainder pasted down to form a complete moon 25 as shown in Fig. 4c.

Fig. 5 illustrates a variety of forms of stencils, masks, and design masks which may be employed in connection with this treatment and the various 75 modifications of the general method shown and

described heretofore. In Figs. 5a, b, and c are the forms employed and shown in the above described methods, in which a and b may be reversed so as to slenderize the nail and the sides of these stencils may be used as straight edges, 5 and c may be used as a moon stencil instead of stencil 11 in Fig. 1b or instead of stencil 18 in Fig. 2b. Fig. 5e shows a form of mask or stencil which has a plurality of differently shaped edges and embodies the stencil configurations shown 10 in Figs. 1, 2, 3, and 4 and in addition has a point 26 which could be used as a tip stencil in place of the stencil 19 when the tip of the nail is cut in a pointed manner, or as a moon stencil in place of the stencil 11 in Fig. 1b. 15

Figs. 5d, f, g, h, and i illustrate a series of different forms of design masks which may be employed on the nail when it is desired to impose thereon a definite design to enhance the beauty of the nail and this ornamental design mask may 20 in the manners described above be colored or tinted in a contrasting manner if desired. It is understood that these design masks may be put on before the color is applied or after the color is applied and may be removed or left permanently on the nail, to suit the taste of the user. 25

All these stencils, masks, and design masks above described are preferably made of a suitable material which is flexible and impervious to the usual polishes, removers, cleansers and the like employed in nail treatment so that when in place to cover or protect a predetermined portion of the nail, the polish, removers, cleansers, etc., can not get through or around the stencil, mask, or design mask to affect the covered or protected 30 area. These stencils, masks or design masks, may be made of any suitable material such as a cellulosic substance, waxed papers, masking tape, and the like, and may be transparent, translucent, or opaque and of any color, and may be 40 designed to be removable or permanent on the nail. They may be cut ready for use or cut by the user at will.

Preferably and necessarily the surface of the stencil, mask, or design mask employed adjacent and in contact with the nail or the nail coating must be supplied with an adhesive which may be applied thereto when the device is made or just before the device is to be applied to the nail. This adhesive is preferably one which is non-drying, at least when the temporary form of the stencil, mask, or design mask is being used, so that it can be removed with ease from the nail and will not leave any adhesive or portion of the device on the nail or on the underlying polish 55 as it is being removed. This adhesive furthermore must be such as to resist the action of the usual polishes, removers, lacquers, etc., employed so that its adhesive action is not affected by coming into contact with such substances. Such 60 adhesives may be such as various gums, gum tragacanth, gum acacia, Irish moss, starches, sugars, latex bases, etc., either drying or non-drying as the use may demand as above indicated. Thus in effect the adhesive on the mask 65 forms an impenetrable barrier to the invasion into the protected area of any of the nail treating substances mentioned and therefore it is possible that the adhesive itself without the mask may in desired instances, be employed and 70 achieve these results.

When a permanent mask, stencil or design mask is employed in final position to be permanently applied to the nail, a colorless or other substance such as a liquid of a fixing nature may 75

be applied over the whole nail including the permanent device so as to more firmly hold the device in place as well as to smooth the surface level between the top of the device and the level 5 of the remaining portion of the nail.

When the design mask shown in Fig. 5*i*, containing the letter G thereon, is to be used, this will be in cases where it is desired to cover or protect the whole nail as a sort of ornamental 10 protecting covering which adds to the beauty of the nail and protects it from contact, blows, and damage when the other nails are being treated. It also is used to cover and protect nails, which have been damaged or broken, while they are 15 healing up. This ornamental design mask 29 is of the material above mentioned and supplied with any of the desired adhesives mentioned and is shaped to be long enough to cover and protect the entire nail and to be adhered thereto after 20 being cut exactly to the desired size of the nail. It may be supplied with any ornamental design thereon such as shown by the letter G and may be colored as desired.

In the Fig. 6, there is shown a finished nail 25 which has been treated generally according to the method shown in Fig. 2, and in which the stencil employed is of the general shape and type shown in Fig. 2*b* but in particular is of a shape to produce an arrow or spear head design 30 in color on the nail. This is not only ornamental and artistic but the spear point shown does give a positive effect of lengthening or slenderizing the nail in addition to adding to its beauty. To achieve this result, the nail is treated with the 35 color 18 over its entire surface and then a spear head shaped stencil or mask is placed on the nail with its tip or apex coinciding with the front edge of the nail. After the stencil is in place then the rest of the nail exposed is wiped 40 with any suitable removers as above mentioned leaving the uncolored exposed portions as shown in Fig. 6 and leaving a spear head design on the nail as shown by the number 30. The surrounding portions or areas may if desired be left color- 45 less or may be produced in contrasting colors in accordance with any of the methods above described and by using any of the stencils, masks, or design masks above set forth. If found desired more than one stencil may be used in producing this effect and in accordance with the 50 methods and devices set forth above.

While the invention has been described in detail and with respect to a present preferred form thereof, it is not to be limited to such details and 55 forms since many changes and modifications may be made in the invention without departing from the spirit and scope of the invention in its broadest aspects. Hence it is desired to cover any and all forms and modifications of the in- 60 vention which may come within the language or scope of any one or more of the appended claims.

What I claim is:

1. A device for treating nails which comprises a mask of material impervious to nail treating 65 substances and a non-drying adhesive resistant to the same substances disposed on the surface of the mask which is to be pressed into intimate contact with the nail.

2. A method of treating nails which comprises 70 covering one portion of the nail with adhesive material resistant to nail treating substances while other portions are being treated whereby a clear, definite and accurate line of demarcation between the several sections may be produced.

75 3. A method of treating nails which comprises

protecting one portion of the nail with adhesive material acting as a resistant barrier to nail treating substances while the other portions are being treated whereby a clear definite and accurate line of demarcation between the several sections 5 may be produced.

4. A device employed in the treatment of nails which comprises a mask of relatively thin pliable material and a non-drying adhesive resistant to nail treating substances disposed on its under 10 surface to be pressed into intimate contact with the area of the nail to be protected while other areas are being treated.

5. A device employed in the treatment of nails which comprises a mask of relatively thin pliable 15 material of a quality to resist nail treating substances and a non-drying adhesive resistant to nail treating substances disposed on its under surface to be pressed into intimate contact with the area of the nail to be protected while other 20 areas are being treated.

6. A method of treating nails which comprises applying a substance to at least the moon section of the nail, subsequently covering a portion of the nail with adhesive material resistant to 25 nail treating substances, then wiping the exposed portions of the nail, then applying another substance to the exposed portions, and then removing the covering.

7. A method of treating nails which comprises 30 applying a substance to the entire nail, placing a plurality of stencils resistant to nail treating substances over the middle portion of the nail, wiping the end portions of the nail beyond the stencils, applying an additional substance to the 35 wiped portions, and then removing the stencils.

8. A method of treating nails which comprises covering the entire nail with a substance, and placing a stencil resistant to nail treating substances over the middle portion of the nail adjacent the moon portion, wiping the moon portion of the nail, and then removing the stencil. 40

9. A method of treating nails which comprises covering the moon portion with a shaped stencil by means of adhesive resistant to nail treating 45 substances, applying a substance to the exposed portion of the nail, and then cutting off the portions of the stencil which extend beyond the moon portion and leaving the remainder of the stencil on and covering the moon portion. 50

10. A device for treating nails which comprises a stencil of material resistant to nail treating substances, used in the treatment of the nail to produce a colored design thereon tapering from the base to the tip of the nail. 55

11. A method of treating and slenderizing nails which comprises covering the entire nail with a color, placing a stencil of material resistant to nail treating substances over the nail having a tapered shape which tapers off to a point coincident with the tip of the nail, wiping the exposed portions of the nail, and then removing the stencil. 60

12. A device for treating nails which comprises a stencil or mask of predetermined form adapted to cover a predetermined portion of the nail while the other portions are being treated, the mask being of material impervious to nail-treating substances, and provided with adhesive adjacent the nail and of material insoluble in nail treating substances, said adhesive being of a non-drying nature, such as water soluble adhesives of animal or vegetable glue and the like. 65

13. A device for treating nails which comprises a mask of material impervious to nail 70

treating substances such as alcohol, acetone, and the like, and a non-drying adhesive resistant to the same substances disposed on the surface of the mask which is to be pressed into intimate contact with the nail.

5 14. A nail stencil for use in manicuring to cover and protect a portion of the nail comprising a flexible strip having a part shaped to cover said portion of the nail, said strip having an adhesive coating at least on said nail covering part for securing the same directly to the portion of the nail to be covered.

10 15. A nail stencil adapted for a single use in manicuring to cover and protect substantially the moon portion of the nail comprising a flexible strip having an end part shaped to substantially cover said portion of the nail, said strip having a pressure-sensitive adhesive coating at least on said nail covering part for removably securing the same directly to said portion of the nail.

15 16. The method of nail treating comprising affixing a mask with adhesive directly to the nail, said mask being of opaque material and of any desired color, and said mask and nail treated with a protective covering substance.

20 17. The method of nail treating comprising affixing a mask with adhesive directly to the nail, said mask being of transparent material and of any desired color, and said mask and nail treated with a protective covering substance.

25 18. The method of nail treating comprising affixing a mask with adhesive directly to the nail, said mask being of translucent material and of any desired color, and said mask and nail treated with a protective covering substance.

30 19. The method of nail treating comprising affixing a mask with adhesive directly to the nail, said mask being of opaque material and of any desired color, and said mask and nail treated with a transparent protective covering substance.

35 20. The method of nail treating comprising affixing a mask with adhesive directly to the nail, said mask being of transparent material and of any desired color, and said mask and nail treated with a transparent protective covering substance.

40 21. The method of nail treating comprising

affixing a mask with adhesive directly to the nail, said mask being of translucent material and of any desired color, and said mask and nail treated with a transparent protective covering substance.

5 22. The method of nail treating comprising affixing a mask with adhesive directly to the nail, said mask being of opaque material and of any desired color, and said mask and nail treated with a translucent protective covering substance.

10 23. The method of nail treating comprising affixing a mask with adhesive directly to the nail, said mask being of transparent material and of any desired color, and said mask and nail treated with a translucent protective covering substance.

15 24. The method of nail treating comprising affixing a mask with adhesive directly to the nail, said mask being of translucent material and of any desired color, and said mask and nail treated with a translucent protective covering substance.

20 25. The structure set out in claim 14 in which the stencil is made of transparent material and may be permanently affixed to the nail.

25 26. The structure set out in claim 14 in which the stencil is made of translucent material and may be permanently affixed to the nail.

30 27. The structure set out in claim 14 in which the stencil is made of opaque material and may be permanently affixed to the nail.

35 28. The structure set out in claim 14 in which the stencil is made of opaque material and of any color desired and may be permanently affixed to the nail.

30 29. The structure set out in claim 14 in which the stencil is made of transparent material and of any color desired and may be permanently affixed to the nail.

40 30. The structure set out in claim 14 in which the stencil is made of translucent material and of any color desired and may be permanently affixed to the nail.

45 31. The method of nail treatment which comprises cleansing the nail, affixing a mask with adhesive directly to the nail and covering said nail and mask with a protective substance.

CONRAD C. CALVIN.
